(57) **CLAIM**

The ornamental design for a rear combination lamp for an automobile, as shown and described.

DESCRIPTION

FIG. 1 is a perspective view of a rear combination lamp for an automobile, showing my new design;

FIG. 2 is a front elevational view thereof;

FIG. 3 is a top plan view thereof; and,

FIG. 4 is a left side elevational view thereof.

The claimed design is indicated by the relatively dark portion, while the relatively light portions, encapsulated by broken lines, form no part of the claimed design. The broken lines in the drawings form no part of the claimed design.

1 Claim, 4 Drawing Sheets
